TETHERED BAG FOR AN EXERCISING GAME OR THE LIKE

Heinrich Wilhelm Bernhard, 84 Broadway,
Elwood, Victoria, Australia

Filed Sept. 8, 1971, Ser. No. 178,849

Term of patent 14 years

Int. Cl. D21—02

U.S. Cl. D34—5 C

FIG. 1 is a front perspective view of a tethered bag for an exercising game or the like showing my new design;

FIG. 2 is a front elevational view thereof, the rear being substantially a mirror image thereto; and

FIG. 3 is a side elevational view thereof.

I claim:

The ornamental design for a tethered bag for an exercising game or the like, as shown and described.
